UNITED STATES PATENT OFFICE

GEORGE GODDU, DECEASED, LATE OF WINCHESTER, MASSACHUSETTS, BY ISABELLE W. GODDU, EXECUTRIX, OF WINCHESTER, MASSACHUSETTS, ASSIGNOR TO UNITED SHOE MACHINERY CORPORATION, OF PATERSON, NEW JERSEY, A CORPORATION OF NEW JERSEY

MACHINE FOR SHAPING UPPERS OVER LASTS

Application filed May 31, 1932. Serial No. 614,444.

This invention relates to machines for use in the manufacture of shoes for shaping uppers over lasts. It is herein illustrated as applied to a lasting machine of the progressive type which operates successively on different portions of a shoe, and more particularly to a machine constructed for the most part substantially as disclosed in Letters Patent No. 1,796,451, granted on March 17, 1931 upon an application of George Goddu; but it is to be understood that in its more general aspects it is not thus limited in its applicability.

Machines of the character disclosed in the above-mentioned Letters Patent comprise in their organization a gripper for pulling an upper over a last successively in different locations along the edge of the last bottom, a device that is movable inwardly over the bottom of the last in time relation to each upper-pulling operation to lay the marginal portion of the upper over a sole having a lip thereon, and means for driving a staple from the overlaying device through the upper and the lip of the sole after each overlaying operation and for clinching the legs of the staple on the inner face of the lip. The overlaying device, as therein disclosed, is movable inwardly over the sole in a direction somewhat inclined toward the bottom face of the last and is provided with a guideway from which the staple is driven through the upper and the lip in the same inclined direction.

The present invention, in one aspect, provides a novel construction such that the staple or other fastening used to fasten the upper to the lip of a sole in a machine for shaping uppers over lasts (for example, a machine of the above-mentioned character) is driven in a direction at an angle to the direction of the inward movement of the overlaying device in laying the upper over the sole. As applied to an organization such as illustrated, in which the overlaying device is movable as above described in a direction inclined toward the bottom face of the last, the invention thus provides means whereby the fastening is driven in a direction at a greater angle to the bottom face

of the last than the direction of the movement of the overlaying device. This is of particular advantage, for example, in operating on turn shoes to fasten the upper to the inwardly inclined inside channel lip of the sole, since the fastenings may be driven through the inclined lip in directions substantially perpendicular to the lip and clinched close to the base of the lip without the necessity of moving the overlaying device inwardly over the sole in a direction at a greater angle to the bottom of the last than is desirable for the best results in the overlaying operation. The invention is accordingly herein illustrated by reference to the lasting of that kind of shoe, but it is to be understood that it is not thus limited but may be utilized with advantage in operating on shoes of other kinds, such as welt shoes having shouldered insoles, or welt shoes having insoles of the more usual type in case, for example, it is desired to clinch the fastenings very close to the base of the lip. It is further to be understood that the invention is not necessarily limited to an organization in which the overlaying device moves inwardly over the shoe bottom, as illustrated, in a direction inclined to the bottom face of the last, nor to an organization in which the overlaying and fastening means operate in combination with a gripper that pulls the upper over the last. Furthermore, while the fastenings illustrated are staples, fastenings of other kinds may be utilized consistently with the objects of the invention.

The novel features of the invention will now be more particularly described by reference to the accompanying drawings, and thereafter pointed out in the claims.

In the drawings,

Fig. 1 is a view in side elevation of a portion of a machine of the type disclosed in the above-mentioned Letters Patent with the invention embodied therein;

Fig. 2 is a view substantially in front elevation of a portion of the structure shown in Fig. 1, with parts in section on the line II-II of Fig. 1 and other parts broken away;

Fig. 3 is a view in side elevation of a portion of the structure shown in Fig. 1 with

the parts in the positions that they occupy at the end of the overlaying operation, portions of the structure being broken away to show more clearly the means with which a machine of the illustrative type is provided for transferring the staple from the position in which it is formed to the position in which it is driven;

Fig. 4 is a view similar to Fig. 3, but showing the staple-transferring means at the end of its transferring movement;

Fig. 5 is a section on the line V—V of Fig. 3;

Fig. 6 is a section on the line VI—VI of Fig. 1, showing more clearly the means for driving and clinching the staple; and

Figs. 7 and 8 are views illustrating respectively the positions of parts of the machine at different times in operating on a shoe, the shoe shown being a turn shoe.

As more fully disclosed in the previously mentioned Letters Patent, the machine herein shown includes in its organization a gripper comprising jaws 10 which are operated to grip and pull the upper heightwise of the last and inwardly over the sole in different locations successively along the edge of the last bottom as the operator presents and holds the shoe in different positions for successive lasting operations. The shoe is supported against the pull of the gripper and is positioned in proper relation to the different operating instrumentalities by a sole rest member 12 which engages the sole on the inner face of the lip *a* and in operating on work of the type illustrated extends into the inner channel adjacent to the lip, this member being provided with clinching faces 14 (Fig. 6) for engaging the legs of the staple and clinching them on the inner face of the lip. In the construction shown the member 12 is so shaped as to provide a comparatively thin lower edge portion to adapt it readily to extend substantially to the bottom of the channel in the sole and its clinching faces are arranged with reference to the more steeply inclined direction of drive of the staple (hereinafter more particularly referred to) to clinch the legs close to the base of the lip.

For laying the marginal portion of the upper inwardly over the sole in time relation to each upper-pulling operation of the gripper there is provided an overlaying device comprising a staple-guiding nozzle 16 supported as described in the previously mentioned Letters Patent on a slide 18 which is movable along guideways 20 provided by a bracket 22 fast on the head of the machine. These guideways are inclined in such relation to the shoe positioned and held as hereinabove described that the nozzle 16 engages the upper initially a substantial distance above the sole and moves in a direction inclined toward the bottom face of the last in laying the upper inwardly over the

sole and against the lip, the direction of the movement of the nozzle being indicated by the line *b* in Figs. 7 and 8. The nozzle 16 is provided with a guideway 24 for the staple in alinement with a staple guiding face 26 on a member 28 carried by the slide 18. The staple is driven by a driver 30 movable along the face 26 and the guideway 24 and carried by a slide 32 movably mounted on the member 28. The driver is operated by a swinging arm 34 which in the construction herein shown is connected by a link 36 to the slide 32, the arm being operated by a torsion spring 38. To tension the spring and retract the driver the arm 34 is held back by a latch 40 when the slide 18 is moved forwardly to cause the nozzle 16 to lay the upper over the sole, the latch being carried by a lever 42 which is operated after the forward movement of the slide 18 to cause a screw 44 on the slide to disconnect the latch from the arm 34 and thus release the arm to the action of the spring 38. Carried also by the slide 18 is an outside former comprising plates 46 which cooperate with a stationary inside former 48 to form a staple in the forward movement of the slide, a member 50 being further provided to assist in forming the head of the staple against the inside former, as shown in Fig. 5. The staple is thus formed in a location above the path of movement of the driver 30 and must accordingly be transferred to a position in alinement with the driver. For this purpose the plates 46, which have in their inner faces recesses of less depth than the thickness of the staple wire and in which the legs of the staple lie when they are formed, are carried by a slide 52 which is movable downwardly at the end of the overlaying and staple forming operations to carry the staple to a position in which it rests on the guiding face 26, as illustrated in Fig. 4. It is at this point in the operation that the staple is driven as hereinabove described. For a more complete understanding of the construction and manner of operation of the parts thus far described reference may be made to the previously mentioned Letters Patent.

For purposes of the present invention the construction shown is such that the face 26 of the member 28 for guiding the staple and the driver 30, and the alined guideway 24 of the nozzle 16, instead of being parallel to the direction of movement of the slide 18 and of the nozzle in laying the upper over the sole as in the earlier construction, are inclined at a greater angle to the bottom face of the last than the direction of such overlaying movement, the driver 30 also being inclined at the greater angle. This will be evident by reference to Figs. 7 and 8 where, as previously stated, the line *b* indicates the direction of movement of the slide 18 and the nozzle 16. In operating on turn shoes, as illustrated,

this affords provision for the driving of the staple through the inwardly inclined lip of the sole in a direction substantially perpendicular to the lip, and also for the clinching of the staple legs very close to the base of the lip by the member 12 specially constructed for this purpose, without the necessity of undesirably increasing the angle between the bottom face of the last and the direction of the overlaying movement of the nozzle 16, the best results being obtained in the overlaying operation from movement of this nozzle in a direction inclined at only a comparatively small angle to the bottom face of the last.

While the invention is thus illustrated and described with particular reference to the lasting of turn shoes, as affording very satisfactory means for lasting a shoe of that character, it will be understood that the construction disclosed may likewise be used with advantages in operating on shoes of other kinds, as hereinbefore suggested. The term "sole" as used in the claims is therefore not to be construed as limited to the single sole of a turn shoe, but as applicable generally to that shoe bottom part over which an upper is lasted, including the insole of certain types of shoes.

Having described the invention, what is claimed as new and desired to secure by Letters Patent of the United States is:

1. In a lasting machine, the combination with means for pulling an upper over a last successively in different locations along the edge of the last bottom, of a device movable inwardly over the bottom of the last in a direction inclined toward the bottom face of the last to lay the marginal portion of the upper over a sole on the last and against a lip on the sole in time relation to each upper-pulling operation, means for driving fastenings through the upper and said lip each in a direction at a greater angle to the bottom face of the last than the direction of the inward movement of said device in laying the upper over the sole, and means for clinching each fastening on the inner face of the lip.

2. In a lasting machine, the combination with means for pulling an upper over a last successively in different locations along the edge of the last bottom, of a device movable inwardly over the bottom of the last in a direction inclined toward the bottom face of the last to lay the marginal portion of the upper over a sole on the last and against a lip on the sole in time relation to each upper-pulling operation, said device being provided with a guideway for fastenings inclined at a greater angle to the bottom face of the last than the direction of the inward movement of the device in laying the upper over the sole, a driver movable in a direction at the same inclination to the bottom of the last as said guideway to drive a fastening

through the upper and the lip of the sole in time relation to each overlaying operation, and means for clinching each fastening on the inner face of said lip.

3. In a lasting machine, the combination with means for pulling an upper over a last successively in different locations along the edge of the last bottom, of a device movable inwardly over the bottom of the last in a direction inclined toward the bottom face of the last to lay the marginal portion of the upper over a sole on the last and against a lip on the sole in time relation to each upper-pulling operation, said device comprising a staple-guiding nozzle having a guideway for staples inclined at a greater angle to the bottom face of the last than the direction of the inward movement of the device in laying the upper over the sole, means for driving a staple from said nozzle through the upper and the lip of the sole in the direction of said guideway, and an anvil for clinching the legs of the staple on the inner face of said lip.

4. In a lasting machine, the combination with means for pulling an upper over a last successively in different locations along the edge of the last bottom, of a device movable inwardly over the bottom of the last in a direction inclined toward the bottom face of the last to lay the marginal portion of the upper over a sole on the last and against an inwardly inclined lip on the sole in time relation to each upper-pulling operation, said device being provided with a guideway for fastenings extending in a direction at an angle to the direction of the inward movement of the device in laying the upper over the sole to guide each fastening in a path substantially perpendicular to the inclined lip, means for driving a fastening in the direction determined by said guideway through the upper and the lip of the sole in time relation to each overlaying operation, and means for clinching each fastening on the inner face of said lip.

5. In a lasting machine, the combination with means for pulling an upper over a last successively in different locations along the edge of the last bottom, of a device movable inwardly over the bottom of the last to lay the marginal portion of the upper over a sole on the last and against an inwardly inclined lip on the sole in time relation to each upper-pulling operation, said device comprising a staple-guiding nozzle having a guideway for staples inclined relatively to the direction of the inward movement of the device in laying the upper over the sole and relatively to the bottom face of the last to guide each staple in a path substantially perpendicular to the inclined lip, a driver movable along said guideway to drive a staple through the upper and the lip of the sole in time relation to each overlaying operation,

and an anvil for clinching the legs of the staple on the inner face of said lip and for positioning the shoe by engagement with the lip.

6. In a machine for shaping uppers over lasts, a device movable inwardly over the bottom of a last to lay the marginal portion of an upper over a sole on the last and against an inwardly inclined lip on the sole, said device being provided with a guideway for 10 fastenings inclined relatively to the direction of the inward movement of the device in laying the upper over the sole and relatively to the bottom face of the last to guide each fastening in a path substantially perpendicular to the inclined lip, a driver movable to drive a fastener through the upper and the lip of the sole in the direction determined by said guideway, and a member for clinching the fastening on the inner face of 15 said lip and for positioning the shoe by engagement with the lip.
7. In a machine for shaping uppers over lasts, a device movable inwardly over the bottom of a last in a direction inclined toward 20 the bottom face of the last to lay the marginal portion of an upper over a sole on the last and against an inwardly inclined lip on the sole, said device comprising a staple-guiding nozzle provided with a guideway for 25 staples extending in a direction at an angle to the direction of the inward movement of the device in laying the upper over the sole to guide each staple in a path substantially perpendicular to the inclined lip, a driver movable along said guideway to drive a staple from 30 said guideway through the upper and the lip of the sole, and means for clinching the legs of the staple on the inner face of 35 said lip.

- 40 8. In a machine for shaping uppers over lasts, a device movable inwardly over the bottom of a last in a direction inclined toward the bottom face of the last to lay the marginal portion of an upper over a sole on the last and 45 against a lip on the sole, means for driving a fastening from said device through the upper and said lip in a direction inclined at a greater angle to the bottom face of the last than the direction of the inward movement 50 of the device in laying the upper over the sole, and means for clinching the fastening on the inner face of the lip.

9. In a machine for shaping uppers over lasts, a device movable inwardly over the bottom of a last in a direction inclined toward the bottom face of the last to lay the marginal portion of an upper over a sole on the last and against a lip on the sole, said device being provided with a guideway for 55 staples inclined relatively to the direction of the inward movement of the device in laying the upper over the sole, a driver for driving a staple through the upper and the lip of the sole in the direction determined by 60 said guideway, and means for clinching the 65

legs of the staple on the inner face of said lip.

In testimony whereof I have signed my name to this specification.

ISABELLE W. GODDU, 70
Executrix of the Will of George Goddu,
Deceased.
